State of Rhode Island and Providence Plantations.

Letters Patent

The subscriber, refused to invent, selling, using and making, and of the same
containing a description in the words of the said Seth Brinman himself of
his improvement in the Thread frame for spinning, Cotton.

To all persons, to whom these presents shall come, Seth Brinman,
of Providence, in the County of Providence and State of Rhode Island.

Gentlemen Bonds Drawing: Be it known that the said Seth Brinman
has invented and constructed, made and applied to a new and useful
Improvement in the mode of spinning Cotton Specified in the words
following to wit. This improvement in the machine commonly called
the Thread frame consists in taking the thread from the rollers in the
middle of the balance flier. Then running through the gear gear and pulley
which is in the said balance flier, through a hole one inch long; and
thence passing over the outside of the hole of the balance flier until it come
to another hole one inch from the lower end of the same balance flier, through
which it passes to the end of the flier, and into the bobbin which receives
it in manner following, viz. By a band taken from the door in the case
box of the frame, there running to a shaft under a joint that holds the
lower end of the balance flier. There is an improvement in the position of the
spindle forming instead of a right angle with the machine, an angle of ap-
ly five degrees only. These spindles may be turned independent spindles,
so constructed to move round fast or slow as occasion may require, insel-
ling the bobbin in the manner following, viz. Take a bar of wood about one
inch wide and of sufficient length and place a little bark of the spindle
in this bar of wood small blocks of iron about one inch in height are set
in, and small wooden springs about five inches in length against each spindle
to thumb them into each block, and bear against the springs above
and which springs are intended to bear directly against the spindles over the
middle under the spindle. The bearing of the wooden spring instead of being
against the spindle, as former may be against the lower part of the bobbin
the last mentioned method is however superior to this first. (See
Drawing)

Jan. 16, 1832

I claim as original with me in this invention is, the method of tracing against the spindle or bobbin with springs, a method which is perfectly simple, and without the application of which the machine as above described, but cannot be operated to advantage.

In testimony that the above is a true specification of my said improvement, as above described, I have hereunto set my hand and seal the tenth day of February in the year of our Lord Eighteen hundred and thirty six.
